UNITED STATES PATENT OFFICE.

JOSEPH YOLO, OF YAKIMA, WASHINGTON.

SPIRAL SPRING WRAPPER.

Application filed December 22, 1923. Serial No. 682,178.

To all whom it may concern:

Be it known that JOSEPH YOLO, citizen of the United States, residing at Yakima, in the county of Yakima and State of Washington, has invented certain new and useful Improvements in Spiral Spring Wrappers, of which the following is a specification.

This invention relates to a spiral wrapper for vehicle springs and it has for its object to provide a device of this nature which will be of simple construction, economical to manufacture, will present a slightly appearance in use, will keep out dust and dirt and will retain lubricants just as effectually as more expensive devices heretofore employed.

It is a well known fact that the source of most of the squeaks in automobiles is in the springs. The task of lubricating the springs is a more or less troublesome one and the practice is becoming increasingly widespread of enclosing the springs in casings of leather, rubber or other flexible material, said casings serving to exclude dust and dirt and to retain the lubricant for the springs.

Many of the casings proposed for this purpose are quite expensive to manufacture and, since it is extremely difficult to get them to snugly fit the springs, they are more or less bunglesome and unsightly in appearance. Furthermore where a preformed casing is employed, many different sizes must be manufactured to fit the different sizes and types of springs on the market.

In the accompanying drawing:

Fig. 1 is a longitudinal sectional view illustrating my invention applied to a part of an automobile spring;

Fig. 2 is a transverse sectional view through the strip hereinafter described; and

Fig. 3 is a view in side elevation illustrating a vehicle spring partly wound with the strip of the present invention.

Like numerals designate corresponding parts in all of the figures of the drawing.

Referring to the drawing it will be seen that the strip of the present invention comprises a strip of relatively thin fabric 5 which may be artificial leather, such as the well known fabrikoid or pantasote, canvas or indeed any other suitable fabric. A strip of relatively thick felt is cemented onto the fabric back 5, said felt being indicated at 6. The felt is offset with respect to the fabric back 5 which projects beyond said fabric back, as indicated at 6^a. A coat-

ing of wax composition 7 covers the exposed face of the felt and, in addition, overlaps the fabric strip 5, as indicated at 8. That face of the fabric strip 5 indicated at 9 and which is the part of the fabric strip left exposed by the offsetting of the felt strip is also coated with the wax composition. This wax composition is preferably composed of paraffin, bees-wax, linseed oil and red lead for coloring, but it is to be understood that the invention is not limited to the use of this particular composition, since it is manifest that any suitable comparatively soft and water repellent substance may be used.

In use, this strip, illustrated in Fig. 2 is wound in spiral formation about the spring to be protected, which is indicated at 10. The end of the strip adjacent the outer end of the spring is clipped in place by a clamp 11 of a usual and well known construction and which may be of the type of the ordinary hose clamp, on the market. And this clamp also secures an oil cup 12 in position the spout 13 of said oil cup extending beneath the clamp and discharging its contents at such point that the felt strip will receive the same and distribute it throughout the length of the spring. An oil and fluid tight joint is formed by the wax composition the felt strip being pressed snugly against the leaves of the springs with the edges of one convolution closely abutting the edges of adjacent convolutions and with the wax portions of the inner face of one convolution bearing upon and in firm engagement with the wax portions of the exterior face of the preceding convolution. By virtue of this arrangement a water and dust proof joint is had and, in addition, the spiral wrapping is caused to hug the spring closely.

Before the wrapping of the spring is started the felt strip 14 having a fabric back 14^a is preferably disposed beneath the spring 10 and is wrapped into place along with the wrapping of the spring proper. This prevents the action of the spring leaves from wearing the wrapper through and also aids in making the wrapper more oil proof. By making the wax composition of a distinctive color it is rendered readily visible and that portion of the wax which overlies the backing 5 at 8 constitutes a gauge to indicate the point to which the next succeeding convolution is to be wrapped. In other words, when the next convolution is brought

2

around that part indicated at 9 is caused to overlap the part 6^a and 8 and since the felt is thicker than the fabric 5, it follows that when this fabric is tightly drawn upon it 5 will compress the felt firmly upon the leaves of the spring and this further aids in the joints being made water and oil tight. The inner end of the wrapping may be secured in position in any desired manner though I 10 will preferably use a clamp of the character of that indicated at 11.

However, it is to be understood that the invention is not limited to any particular way of holding the ends of the wrapper in 15 place, but consists rather in the idea of providing a spiral wrapper of this character irrespective of the particular material of which it is made or how it is held in place.

It is to be understood that the invention 20 is not limited to the precise construction set forth but that it includes within its purview whatever changes fairly come within either the terms or the spirit of the appended claims.

25 Having described my invention what I claim is:

1. A protective wrapper for vehicle springs of spiral formation having a wax-like composition along one edge to form a 30 fluid-tight joint.

2. A wrapper of the character indicated adapted to be wrapped around a spring, of spiral formation and consisting of a relatively thin outer fabric strip and a thicker 35 inner felt strip the two being secured together in overlapping relation, the width

of the felt strip being nearly equal to the width of the fabric strip so that the felt strip will have its edges in contacting relation along the spring and the width of the fabric strip being such with relation to the felt strip that the fabric completely covers and houses the felt strip. 40

3. A structure as recited in claim 2 where- 45 in the overlapping portions of the said strips are coated with a wax-like composition.

4. A structure as recited in claim 2 where- 50 in the overlapping portions of the strips are coated with an adhesive water proof composition.

5. In combination a strip adapted to be wound about a spring in spiral formation, 55 a clamp for securing the strip on said spring and an oil cup held in position by said clamp and in position to discharge its contents into said wrapped strip.

6. A strip of the character described 60 adapted to be wound about a spring in spiral formation, an oil cup and a clamp for holding the end of the strip and for holding said oil cup in operative relation to said strip to discharge the contents of the oil cup into the interior of said strip after the 65 latter has been wrapped.

In testimony whereof he affixes his signature in the presence of two witnesses.

JOSEPH YOLO.
